UNITED STATES PATENT OFFICE.

ANTONI PUKOS, OF DEPEW, NEW YORK.

BALLOON-BALLASTING WEIGHT.

1,257,529.

Specification of Letters Patent. Patented Feb. 26, 1918.

Application filed October 24, 1917. Serial No. 198,243.

To all whom it may concern:

Be it known that I, ANTONI PUKOS, a citizen of Russia, residing at Depew, in the county of Erie and State of New York, have 5 invented certain new and useful Improvements in Balloon-Ballasting Weights, of which the following is a specification.

The primary object of the invention is the provision of a weight shiftably carried 10 by a balloon and serving as a ballasting and equi-liberating device, whereby the balloon is rendered more stable while floating in the air.

A further object of the invention is the 15 provision of a weight adapted to be elevated and lowered from the car of a balloon or like air craft for changing the center of gravity of the air craft as may be found desirable during the changes in the conditions 20 of the wind.

A still further object of the device is the provision of an easy and inexpensive means for assisting the stability of a balloon or like air craft, the device being operable 25 within the car of the air craft but arranged exteriorly thereof, and consuming but little room within the car of the air craft.

In the drawings forming a part of this application and in which like designating 30 characters refer to corresponding parts throughout the several views,

Figure 1 is an elevational view of a balloon provided with the present device, different positions of elements being illustrated 35 by dotted lines.

Fig. 2 is an enlarged sectional view through a portion of the balloon car and the device carried thereby with parts broken away, and

Fig. 3 is a central horizontal sectional view of the weight member.

My stabilizing device may be employed with different forms of air craft, and is herein illustrated in connection with a balloon 10 having a gas bag 11 and a car 12 suspended therefrom adapted for carrying passengers, the structure forming the present invention being secured to the bottom 13 of the car.

50 A weight 14 preferably spherical in form is suspended centrally beneath the bottom of the car 12 by being axially mounted upon a threaded turn-shaft 15 journaled as at 16 through said bottom 13 and having a stop-

nut 17 at its lower end. The upper un-threaded end portion 18 of the shaft 15 projects within the car 12 and has a hand-wheel 19 upon its free end whereby the shaft 15 may be readily turned by the occupants of the car.

A plurality of guide rods 20 are arranged in parallelism with the shaft 15 secured to the car bottom 13 as at 21 and freely extending through openings 22 provided in the weight 14. The operation of the device will 60 be apparent, as the turning of the shaft 15 by means of the wheel 19 as heretofore set forth will move the weight 14 longitudinally of the shaft 15 by reason of the fact that the rods 20 prevent any revolving of 65 the weight 14. The weight may be normally arranged elevated adjacent the car bottom 13 as illustrated by dotted lines at 14' but in rough weather and during strong winds, when the balloon 10 has a tendency 70 to tip and plunge, in the air, the wheel 19 is turned for lowering the weight 14 to any desired position, such as its extreme lowered position herein illustrated at 14''. It will be understood that the changing of the 75 weight 14 alters the center of gravity of the air craft as the occasion may require. In this manner the weight 14 serves as an equi-liberator for the air craft.

What I claim as new is:

1. In combination with the car of an air craft, a threaded shaft journaled through the bottom of the car, a turn wheel for the shaft arranged within the car, a spherical weight threaded upon the shaft, a stop-nut 90 for the weight at the lower end of the shaft, and guide rods carried by the bottom of the car freely extending through the said weight.

2. A ballasting device for balloons comprising a threaded shaft journaled through the bottom of the car of the balloon, a turn-wheel upon the upper unthreaded end of the shaft, within the car, a stop-nut upon the lower free end of the shaft beneath the 100 car, a weight threaded for longitudinal movement upon the shaft arranged with parallel openings therethrough, and guide rods attached to the turn-shaft and freely positioned through the said openings.

In testimony whereof I affix my signature.

ANTONI PUKOS.
